Primary Examiner — Catherine Tuttle

CLAIM

I claim the ornamental design for a baseball coaching mat, as shown and described.

DESCRIPTION

FIG. 1 is a top plan view of the baseball coaching mat showing my new design; and,

FIG. 2 is a top perspective view showing the design in use. The broken lines showing the human form, ball and glove are for illustrative purposes only; and form no part of the claimed design.

1 Claim, 2 Drawing Sheets
